UNITED STATES PATENT OFFICE.

EWALD MEININGHAUS, OF LANCASTER, NEW YORK.

TARGET APPARATUS.

Application filed February 3, 1922. Serial No. 533,989.

To all whom it may concern:

Be it known that I, EWALD MEININGHAUS, a citizen of the United States, residing in Lancaster, in the county of Erie and State 5 of New York, have invented new and useful Improvements in Target Apparatus, of which the following is a specification.

This invention relates to a target apparatus which is more particularly designed for 10 use in shooting galleries and has the object to provide means whereby moving objects are presented for a person to shoot at in such manner that these objects simulate the actions or movements of the game or wild 15 animals which they represent, and to accomplish this by means which are effective in their operation.

In the accompanying drawings: Figure 1 is a front elevation showing the screen of 20 the target and one of the objects which is to be shot at, arranged in the position which it will occupy when the marksman has made a hit. Figure 2 is a vertical longitudinal section of the apparatus taken on line 2—2, 25 Fig. 3. Figure 3 is a top plan view of the target apparatus. Figure 4 is a vertical transverse section taken on line 4—4, Fig. 2. Figure 5 is a fragmentary top plan view, on an enlarged scale, of the detent means 30 whereby the figure or target of the apparatus at which the marksman takes aim is held in its normal position. Figure 6 is a perspective view of the mechanism whereby the target apparatus is reset preparatory to 35 shooting at the target or figure. Figure 7 is a fragmentary longitudinal section taken on line 7—7 of Figure 3. Figures 8 and 9 are vertical transverse sections, taken on the correspondingly numbered lines in Fig. 5. Figure 40 10 is a fragmentary front elevation of one of the figures or targets showing the same in the position which it occupies when the figure or target is hit by the bullet of a marksman. Figure 11 is a similar view of the 45 same mechanism from the rear and showing the target in full lines in the position it occupies when in its normal operative position ready for the marksman. Figure 12 is a similar view showing the manner in which the 50 target is reset into its operative position after having dropped when properly hit by the bullet of a marksman. Figure 13 is a vertical longitudinal section of a coin operated mechanism for controlling the operation of 55 the target apparatus. Figure 14 is a front elevation of the same. Figure 15 is a ver-

tical transverse section taken on line 15—15, Fig. 13. Figure 16 is a view similar to Fig. 13, but showing the pull bar held in its set position, after a proper coin has been introduced into the mechanism. Figure 17 is a fragmentary vertical section, on an enlarged scale, of the detent means which hold the pull bar in its forward or set position. Figure 18 is a fragmentary longitudinal section, 60 on an enlarged scale, taken on line 18—18, Fig. 15, showing a proper coin in position to permit of setting the target apparatus preparatory to shooting at the target. Figure 19 is a similar view showing the manner in 65 which the pull bar is prevented from being operated in an attempt to set the target if the proper coin has not been introduced into the controlling apparatus. Figure 20 is a fragmentary top plan view taken along line 70 20—20, Fig. 18. Figure 21 is a vertical section on an enlarged scale, of the coin machine showing a coin of the proper dimensions arranged within the same. Figure 22 is a horizontal section of the same, 75 taken on line 22—22, Fig. 21. Figure 23 is a view similar to Fig. 21, but showing a coin of improper size being ejected therefrom, so that the same will not permit of 80 operating the target setting mechanism. Figure 24 is a horizontal section taken on line 24—24, Fig. 23.

Similar characters of reference refer to like parts throughout the several views.

In its general organization this target apparatus comprises a screen in rear of which are arranged the targets, figures or objects which are fired upon by the marksman and in front of this is arranged the mechanism whereby the targets may be reset after being 90 hit.

This screen may be variously constructed, but as shown in Figs. 1, 2 and 3, the same consists of an upright board or panel 95 arranged lengthwise in front of the target space and having its front side provided with the representation of a landscape, or other scene, symbolizing the habitat of the game or wild animals. On the upper part of this screen the same is provided with an opening 31, through which a target or a figure representing game is adapted to be moved and to be exposed for a time, during which the marksman is given an opportunity to aim and fire for the purpose of hitting the bull's eye on the movable target.

That part of the target mechanism which

is arranged in rear of the screen is mounted upon a frame 32 which may be of any suitable construction and also serves as a support for the screen. In the construction 5 shown in the drawings, two movable targets or figures representing wild animals are shown, for example, a rabbit 33 and a deer 34. These two targets are operated individually by mechanism which is substantially 10 alike in its main features, but different in certain details in order to cause the target, in its movement, to simulate the animal or game which it represents.

That part of the mechanism associated 15 with the target 33 representing a rabbit is preferably constructed as follows:

Arranged lengthwise of the upper part of the front of the main frame is a longitudinal track composed preferably of two rails, the 20 central parts 35 of which are horizontal or substantially so, the front end portions 36 thereof are inclined upwardly on a curve, and the rear end parts 37 of which are turned or inclined downwardly on the curve, as 25 shown in Fig. 2. Upon this track is mounted a longitudinally movable carriage which in its preferred form comprises a body 38 and wheels or rollers 39 pivotally mounted on the front and rear ends thereof and provided 30 with peripheral grooves, which are adapted to engage with the rails as the carriage runs over the latter and thereby retain the carriage on the tracks and prevent lateral displacement of the same.

35 The target 33 representing a rabbit is preferably constructed from a sheet or plate of metal, such as steel, which when hit by a bullet will not be broken. This target plate is pivotally mounted upon the carriage 40 so that the same is capable of swinging vertically into and out of its operative position. For this purpose the rear part of this plate is provided with an opening 41 which receives a horizontal transverse shaft 42 which 45 latter is mounted in a bearing 43 on the upper end of a standard 44 secured at its lower end to the top of the carriage body 38. In the normal position of this target plate, the front part thereof is elevated and held 50 in this position by means of a detent device, part of which represents the bull's eye and holds this plate in the position which the animal would assume naturally while running, but when the bull's eye is hit by the 55 marksman the front part of this figure is permitted to drop by reason of the preponderating weight of the same over the rear part thereof and thus simulates the position which the animal would take after being hit.

60 This detent device for holding the target plate in its normal position and releasing the same when hit by the marksman is preferably constructed as follows:

65 45 is a circular opening formed in the front part of the target plate and 46 is the

bull's eye having the form of a plate arranged in rear of the opening 45 in the elevated position of the plate 33. This bull's eye is mounted on the front end of a pin 47 and the rear end of this pin is secured by means of a screw 48 to a block 49 which is carried on the free front end of a leaf spring 50 which is capable of being deflected horizontally in a direction transversely of the apparatus. The rear end of this spring is secured to the upper bearing 43 or some other stationary part of the apparatus. The upper edge of the bull's eye 46 is adapted to engage with a downwardly facing shoulder 51 arranged on the rear side of the target plate 33 immediately above the opening 46 and a shoulder is formed on the under side of a projection which latter has its upper side beveled, as shown at 52 in Fig. 8, so that upon raising the target plate 33 the inclined surface 52, by engaging the bull's eye 46, will deflect the same laterally in a rearward direction and when this projection has passed above the upper edge of the bull's eye and the rear end is again permitted to drop, the shoulder 51 of this projection will engage with the upper side of this bull's eye, as shown in Fig. 8, and thereby hold the target plate 33 in its normal operative position, which the animal is supposed to occupy while running before being shot.

The target 33 representing the figure of a rabbit, for example, is arranged behind the lifting end portion of the upper part of the screen and before the same is fired upon by the marksman, the carriage supporting this figure is moved from the right hand end of the screen toward the left hand end thereof, so that the target plate 33 is momentarily exposed to the view of the marksman through the opening 31 in the screen. If the marksman's bullet hits the bull's eye 46 while the target is thus exposed to view the bull's eye will be shifted from the position shown by full lines in Fig. 8 to the position shown by dotted lines in the same figure, whereby the bull's eye will be disengaged from the shoulder 51 and permit the front end of the target plate 33 to drop by gravity from the position shown by full lines in Fig. 2 to the position shown by full lines in Fig. 1.

After the bull's eye of the target has been thus hit while exposed to the view of the marksman through the opening 31 in the screen the target plate 33 will be restored to its normal horizontal or natural position during the rearward movement of the same along its track by the following means:

Arranged on the front end of a shaft 42 is a lifting arm 53 which is adapted to engage with a pin 54 on the adjacent part of the front side of the target 33. On the rear end of this shaft is arranged a tappet arm 55 which projects downwardly therefrom and is adapted to be lifted by engagement

with a stationary tappet 56 arranged on a part of the main frame adjacent to the rear side of the track of the carriage which supports this target plate. During the forward movement of this carriage and the target plate thereon, the tappet arm 55 moves idly over the tappet 56 and the lifting arm 53 swings away from the lifting pin 54, but during the backward movement of this carriage and the target plate mounted thereon the tappet arm 55, upon engaging with the stationary tappet 56, will be turned in the opposite direction and cause the lifting arm 53 to engage with the lifting pin 54 and thereby raise the target plate 33 from its pendent position shown in Fig. 1 to its elevated position shown by full lines in Fig. 2, so that the target plate will be caught by engagement of the bull's eye 46 with the shoulder 51, thus resetting the target plate 33 in the proper position for the next shot. After the tappet arm 55, during its backward movement, clears the tappet 56, this arm again drops by gravity into its normal pendent position and carries the lifting arm 53 away from the lifting pin 54 into the position shown in Figs. 2 and 9, so that the target plate 33 will be free to drop when the bull's eye plate is again hit by a projectile.

In order to permit the target plate 33 to move vertically freely and at the same time hold it reliably in a definite position so that the shoulder 51 thereon will be reliably engaged with the upper edge of the bull's eye plate 46 when the target plate 33 is raised, a slight rearward pressure is produced upon the target plate 33 so that the same will bear frictionally against the front side of the bearing 43 through the medium of an interposed washer 57 which pressure is produced by means of a spring 58 surrounding the central part of the rock shaft 42 and bearing at its front end against the rear side of the bearing 43 through the medium of the spring 50 while the rear end of this spring bears against a collar 59 secured to the shaft 42 by means of a set screw 60, as shown in Figs. 5 and 9.

Upon now operating the target apparatus, the carriage supporting the target plate is pushed forwardly over the track by mechanical means, but the return or backward movement of the carriage is produced by gravity due to the fact that the track rises from its rear end toward its front end when considered as a whole. In order to prevent the carriage from accidentally moving beyond the front end of the track in case the same is pushed too vigorously, a stop 61 is arranged on the track at the front end thereof, which is engaged by the front end of the carriage and prevents the latter from moving beyond the track.

Various means may be provided for push-

ing the target bearing carriage forwardly over the track, but those shown in the drawings have been found suitable in practice and as there shown the same are constructed as follows:

Arranged adjacent to the rear end of the track just described is a shifting lever which is pivotally supported between its upper and lower arms 62, 63 upon a bracket 64 projecting downwardly from the rear end of this track. The upper arm 62 of this lever is arranged in the path of the body 38 of the carriage which supports the target 33 and the same is connected by means of a spring 65 with an adjacent part of the main frame so that this spring constantly tends to pull this arm forwardly. The movement of the latter in this direction is limited by a stop 66 and the rearward movement of this arm is limited by engagement with a stop 67, both of these stops being arranged on the adjacent part of the track. For the purpose of setting the target for pushing the target bearing carriage forwardly the shifting lever is turned, so that its upper arm 62 moves backwardly and its lower arm 63 moves forwardly during which time the spring 65 is strained and the target bearing carriage is permitted to move by gravity upon following the upper shifting arm 62 into its rear-most position, this movement of the shifting lever being effected by means which are preferably arranged adjacent to the marksman's stand and means being provided for holding this lever in this position until released by the marksman just before shooting at the target. For this purpose a hand operated setting lever 68 is provided which is mounted on a standard 69 arranged adjacent to the place where the marksman stands and has its upper arm connected with the lower arm 63 of the shifting lever by means of a line, wire or cable 70, which is guided between its ends upon a roller 71 arranged on a suitable part of the main frame. Upon swinging the upper arm 68 of the setting lever backwardly, the shifting lever will be turned so that its upper arm 62 is moved backwardly and permits the carriage bearing the target 33 to move backwardly from the position shown by full lines in Fig. 2, to the position shown by dotted lines in the same figure, at which time the spring 65 is strained. Upon shifting the parts into this position, the lower arm of the hand lever 68 moves over the inclined rear face 72 of a stop and then engages with the abrupt front side 73 thereof, as shown by dotted lines in Fig. 6, whereby this lever and the parts associated therewith, are locked in this position, this stop being mounted on a vertically swinging stop lever 74 pivoted at its front end on a bracket 75 and yieldingly held in its elevated position by means of a spring 76 secured to the

bracket 75 and bearing against the under-side of the stop lever 74. When the marksman is ready to shoot, the stop lever 74 is depressed so as to disengage the stop shoulder 73 of the lower arm of the hand lever 68 and when this occurs the resilience of the spring 65 quickly turns the shifting lever so that the upper arm 62 thereof moves forwardly and pushes the carriage supporting the bearing 43 forwardly over the track upon which the same is mounted, at which time the hand lever 68 is shifted from the position shown by dotted lines to that shown by full lines in Fig. 6. The shifting lever remains in this position during the forward movement of the target bearing carriage under the pressure which has been imparted thereto and also during the return movement of the same by gravity so that the upper arm of this lever will serve as a stop and arrest this carriage with a cushioning effect a short distance in front of its rearmost position, as indicated by full lines in Fig. 2. The depression of the stop lever 74 is preferably effected by the foot of the marksman for which purpose a treadle 77 is pivotally supported adjacent to the marksman's place and connected by means of a link 78 or other suitable means with the free end of the stop lever 74 as shown in Figs. 3 and 6.

In order to provide variety and increase the interest in the shooting gallery in which this target apparatus is installed, an additional target of the same general character is provided, which however, is provided with additional features which are constructed to simulate the action, or habits of game of a different type from that of the rabbit just described.

For this purpose the target represented by the plate 34 is constructed in imitation of a deer, the habits of which are such that the same will run for a distance and then come momentarily to a stop, upon hearing a noise and then resume its movement. As shown in the drawings, this deer target 34 is mounted upon a carriage and provided with a catch adapted to hold this target in its normal position, a bull's eye adapted to be hit by a projectile or bullet for releasing the target and permit the same to swing by gravity into its pendent or depressed abnormal position and a restoring or righting device whereby the target is again restored to its normal position during the backward movement of the carriage, all of which parts are of identically the same construction as those previously described with reference to the rabbit-shaped target 33, as well as the description with reference to the operation of the same.

The track over which the carriage runs is in this instance, however, composed of two straight rails 79 which are arranged lengthwise in rear of the rails for the rabbit target 90 and are mounted on the main frame so as to

rise from the right hand end of the track toward the left hand end of the same. The location and length of this track 79 is such that when the deer target 34 is between the right hand or rear end of the same this target will be concealed behind the adjacent part of the screen 30, but when this target is moved forwardly on the front part of this track, this deer target will be exposed to the view of the marksman through the opening 31 in the screen.

The mechanism for pushing the deer supporting carriage forwardly is also identical with that previously described with reference to the mechanism for pushing a rabbit target supporting carriage forwardly and the same reference characters employed in connection with the rabbit target mechanism are therefore applied to the corresponding parts of the deer target, as well as the description of the operation of this mechanism. In addition to pushing the deer target 34 forwardly and upwardly along the track 39 by power and permitting the same to return or move backwardly over this track by gravity, means are provided whereby the deer target is temporarily held in its foremost position in a state of rest and then permit the same to move backwardly by gravity, thereby simulating the habits of a deer when the same assumes a listening attitude when hearing a noise of any kind, such as the breaking of branches or the foot steps of other animals or persons.

The mechanism whereby this is accomplished is constructed as follows:

80 represents a vertically swinging catch which is pivoted at its front end by means of a pin 81 on the main frame adjacent to the front end of the track 79 and provided on its rear part with a longitudinal row of teeth 82 one or the other of which is adapted to be engaged by a downwardly projecting lug or hook 83 on the front part of the body 38 of the supporting carriage of the deer target 34, this catch 80 being yieldingly held in its elevated position so that its teeth 82 are in the path of the lug 83 by means of a spring 84 which is arranged between the underside of this catch and the main frame, the upward movement of this catch, however, being limited by means of a stop rod 85 which passes through the spring 84 and is connected at its upper end with the catch 80 while its lower end is provided with a screw nut 86 engaging with the underside of a part of the main frame, as shown in Figs. 2 and 7. Below the track 79 is arranged a vertically swinging rock lever which is pivoted thereto by means of a pin 87 and has its front arm 88 connected by means of a cord 89 with the free end of the catch 80. Arranged below this rock lever is a longitudinal tilting rail 90 which is connected at its front end by means of a hanger or link 91 with the front

arm 88 of the rock lever while its rear end is connected by means of a link 92 with the rear arm 93 of this rock lever. Along the end of this tilting rail a weight 94 is adapted to run which weight is provided at its upper end with a trolley wheel or roller 95 engaging with the upper side of this tilting rail. The upper arm 62 of the shifting lever associated with the deer target 34 is connected with the rock lever 88, 93 and the tilting rail 90 in such manner that when the arm 62 is moved backwardly the rear or right hand ends of the rail 90 and the adjacent rock lever will be depressed, this being preferably effected by means of a shifting line 96 secured at one end to the upper arm 62 of this shifting lever associated with the deer target and at its other end with the link 92 while its intermediate parts pass around guide pulleys 97, 98 arranged respectively on the inner side of the front part of the track 79 and the floor underneath the same.

In the position of the parts shown in Fig. 2, the deer supporting carriage is arranged a short distance in front of its rearmost position, and the tilting rail 90 inclines downwardly from its rear toward its front end, the weight 94 is arranged in the depressed front end of the rail 90, and the latch or catch 80 is depressed and out of the path of the lug 83 on the deer carriage. This is the position in which the parts are arranged when the marksman finds the apparatus before the same has been set ready for operating the deer target plate 34. In order to prepare the apparatus for causing the target to be set preparatory to shooting at the bull's eye on the same, the marksman pulls backwardly the upper arm of the hand lever 68 associated with the deer target. This causes the upper arm 62 of the shifting lever to move backwardly and permit the deer supporting carriage to move from the position shown by full lines in Fig. 2 to its rearmost position on the track 79 in the manner similar to the movement of the rabbit target 33 from its full line position to its dotted line position shown in Fig. 2. During the backward movement of the shifting arm 62 associated with the deer target a rearward pull is produced by this arm on the line 96 which causes the target rail 90 to be inclined in the opposite direction, thereby causing the weight 94 to slide from the front end of this rail to the depressed rear end thereof, as shown by full lines in Fig. 7. This movement of the rail 90 and the rock lever 88, 93 associated therewith releases the downward pull upon the connecting member 89 and permits the catch 80 to be raised under the action of the spring 84, so that the teeth of this catch are now not arranged in the path of the detent lug 83 in the deer carriage.

Upon now releasing the shifting lever 62, 63 associated with the deer target by de-

pressing the corresponding treadle 77, the companion spring 65 will move this lever in the direction for pushing the deer target forwardly and upwardly along the inclined track 79 and at the same time relax the pulling effect on the line 96. During the last portion of the forward movement of the carriage supporting the deer target, its lug 83 will engage with one or another of the teeth 82 of the detent catch 80 and thereby hold this carriage at rest until such a time as this catch is released from the carriage and the latter is permitted to return by gravity to the rear end of the track 79. As the pull upon the right hand or rear arm 93 of the rock lever is relaxed by reason of the forward movement of the companion arm 62 of the shifting lever and the front arm 88 and those parts mounted thereon in front of the pivot 87 will descend by gravity by reason of the preponderating weight of these parts as compared with the weight of those parts mounted on the rear arm 93 of this lever, which is only sufficient to depress the front arm 88 and take up the slack in the cord, but not sufficient to overcome the tension of the spring 84 so that the catch 80 still remains in engagement with the lock 83 of the deer carriage. Upon, however, depressing the front arm 88 of this rock lever and raising its rear arm 93 the tilted rail 90 will be inclined from its rear end toward its front end into the position indicated by heavy dotted lines 99 in Fig. 7, thereby causing the weight 94 to begin to run down from the rear end of this rail toward the depressed front end thereof. So long as this weight is in rear of the pivot 87 it has no effect upon the position of this rail and the parts associated therewith, but when this weight reaches the front part of the rail 90, the weight of the same together with that of the front arm 88, the rock lever and those parts on the rail 90 arranged in front of the pivot 87 and the link 91 preponderate over the resisting effect of the spring 84 so that the latter is overcome, thereby causing the front parts of the rail and the elements associated therewith to be depressed into their lowermost position, as indicated by dotted lines 100 in Fig. 7, and causing the catch 80 to be pulled downwardly out of engagement from the detent of the deer carriage. When this occurs the deer carriage is released and permitted to run backwardly from the elevated front part of the track 79 to the depressed rear part thereof and into engagement with the upper arm 62 of the respective shifting lever. It will therefore be apparent that by this means the deer carriage has first a forward movement from its concealed position behind the right hand part of the screen to its exposed position behind the opening 31 where the same remains at rest for a short period of time and is then

released and permitted to move backwardly from its exposed position behind the opening 41 to its concealed position behind the right hand side of the screen. This action therefore simulates the habit of the deer and other animals having this peculiarity and gives the marksman an opportunity to shoot at the bull's eye of the deer target, both when running forwardly, standing still and when retreating somewhat in imitation of the condition which would be experienced while actually hunting deer.

If desired, means may be provided whereby the operation of this shooting apparatus can only be accomplished by the insertion of a proper coin or token into a receptacle provided for that purpose. Various means may be provided for accomplishing this purpose, for instance those which are shown in Figs. 13 and 24, which are constructed as follows:

Arranged in front of the target apparatus is a compartment 101 which not only serves as an enclosing casing for the working parts of the coin controlled mechanism, but also as a till for receiving the coins or tokens 102 which are used to operate the apparatus. Extending lengthwise through this casing is a pull rod 103 which has its front end projecting beyond this casing and connected with one end of the pull lines 70 while its rear end projects beyond the rear side of this casing and is provided with a handle 104 for operating it. The pull bar 103 is held in its rearward position by means of a shoulder 105 thereon, which is engaged by a vertically movable catch 106 pivoted on the rear side of the casing and yieldingly moved into its elevated position by means of a spring 107, but is capable of being depressed by a treadle 170 arranged below the front part of the casing and connected by means of a rod 108 with the catch 106. The forward movement of the pull bar 103 is effected by means of the spring 65 which operates the carriage pushing or shifting lever and the last end of the forward movement of this bar is limited by means of a cushioning spring 109 arranged on the front side of the casing and provided with a follower 110 which is adapted to be engaged by a bumper 111 on the handle 104. This backward movement of the pull bar 103, is however only possible when a coin of the proper dimensions has been deposited into the casing or till 101. This coin is inserted through an opening 112 in the top of the casing into the upper end of the coin chute 113 which latter terminates above the slot 114 in the pull bar in the normal position of the parts, but this coin at this time can only pass into this slot and not drop downwardly through the same by reason of a stationary floor 115 being arranged below this slot and forming practically a closure therefor at this time, as shown in Figs. 13 and 15. Upon pulling

this bar 103 forwardly while a coin of this character is arranged within the slot 114 the upper round surface of this coin will be engaged with the rounded front end 116 of the trip arm 117 which latter is arranged in the casing immediately above the rear part of the pull bar 103 and pivoted at its rear end by means of a pin 118 so that its front end can swing vertically under the action of the coin 102 and thus permit the pull bar 103 to move rearwardly without interference and set the target apparatus ready at the same time for the marksman. If, however, no coin has been deposited in the slot 114 and an attempt is made to pull the bar 103 backwardly, the abrupt shoulder 119 of a stop block 120 on the upper side of the pull bar 103 will engage the sharp corner of the trip lever 117, as shown in Fig. 19 and is thereby prevented from effecting a full backward stroke of the pull bar 103, which in turn prevents setting of the target apparatus ready for shooting at the same.

If a coin of the proper dimensions is arranged within the slot 114 the same is carried forwardly by the bar 103 during the operation of setting the target apparatus until the lower part of this coin is carried beyond the shelf 115 which would permit the coin to escape from this slot and leave it clear, ready for receiving the next following proper coin or token.

In the preferred organization of this coin controlling mechanism the treadle 170 is connected with the catches 106 of the two targets, as shown in Fig. 14 so that by depressing one lever it is possible to operate one or the other of the targets, according to whichever has been released by the deposit of the coin or token.

The coin chute is preferably so constructed that it will eject a coin of small diameter therefrom and thus prevent the apparatus from being operated thereby. This is accomplished by cutting out one wall of the coin chute, so as to leave only narrow upright longitudinal flanges 121 thereon, the space between which is greater than the diameter of a small coin 122, but less than the diameter of a coin or token 102 of proper size. A proper coin will therefore pass without interruption downwardly through the coin chute 113 with the opposite edges of its periphery in engagement with the end walls 123, as shown in Figs. 21 and 22. A coin 122 of smaller diameter upon passing downwardly through the chute will, however, be deflected laterally to the slot or opening formed between the flanges 121 by means of a deflecting spring 124 which is arranged lengthwise on one side of the chute and has its upper end secured to the adjacent wall thereof while its lower inclined part is engaged by the coin passing down through the chute and slightly put under tension

thereby. A coin of the proper dimensions will therefore not be influenced by the ejecting spring 124, but a coin of too small a diameter will be pressed sidewise sufficiently by the resilience of the spring to cause this coin to be tilted laterally in the coin chute and discharged through the side opening therein and into the casing instead of being permitted to enter the slot 114 of the pull bar 103, whereby setting of the apparatus by means of an improper coin is prevented.

I claim as my invention:

1. A target apparatus comprising a support, a target pivoted on said support to swing vertically and provided with an opening, and a shoulder, and means for holding said target in its normal position, comprising a bull's eye adapted to be arranged in rear of said opening and to engage said shoulder, and movably supported on said support.

2. A target apparatus comprising a support, a target pivoted on said support to swing vertically and provided with an opening and a shoulder, and means for holding said target in its normal position comprising a bull's eye adapted to be arranged in rear of said opening, and a spring carrying said bull's eye and yieldingly holding the same in engagement with said shoulder and mounted on said support.

3. A target apparatus comprising a track, a carriage movable forward and backward over said track, a standard rising from said carriage and having a bearing, a rock shaft journaled in said bearing, a target plate pivoted on said shaft in front of said bearing and having one side heavier than the other and provided on its heavier side with an opening, and provided on its rear side with a shoulder and on its front side with a pin, a bull's eye plate arranged in rear of said target plate and adapted to engage said shoulder, a leaf spring carrying said bull's eye plate at its front end and secured at its rear end to said bearing, a lifting arm arranged on the front end of said shaft and adapted to engage said pin, a tappet arm arranged on the rear end of said shaft, and a stationary tappet adapted to be engaged by said tappet arm.

4. A target apparatus comprising a track, a carriage movable forward and backward over said track, a standard rising from said carriage and having a bearing, a rock shaft journaled in said bearing, a target plate pivoted on said shaft in front of said bearing and having one side heavier than the other and provided on its heavier side with an opening and provided on its rear side with a shoulder and on its front side with a pin, a bull's eye plate arranged in rear of said target plate and adapted to engage said shoulder, a leaf spring carrying said bull's eye plate at its front end and secured

at its rear end to said bearing, a lifting arm arranged on the front end of said shaft and adapted to engage said pin, a tappet arm arranged on the rear end of said shaft, a stationary tappet adapted to be engaged by 70 said tappet arm, a friction spring surrounding said shaft and bearing at one end against said bearing, and a collar arranged on said shaft, and engaging with the opposite end of said friction spring. 75

5. A target apparatus comprising a track having a horizontal central part, a rising front part and a descending rear part, a carriage movable forwardly and backwardly over said track and having a target, 80 a shifting lever adapted to engage with said carriage, means for retracting said lever, and a spring for projecting said lever.

6. A target apparatus comprising a track having a horizontal central part, a rising 85 front part and a descending rear part, a carriage movable forwardly and backwardly over said track and having a target, a shifting lever adapted to engage with said carriage, means for retracting said lever comprising a hand lever, a line connecting said hand lever with said shifting lever, a detent for holding said hand lever in its retracted position, and a spring for projecting said shifting lever. 90

7. A target apparatus comprising an inclined track which rises from its rear toward its front end, a carriage mounted on said track and having a target and adapted to move backwardly by gravity, means for pushing said carriage forwardly, and means for temporarily holding said carriage in its foremost position comprising a catch arranged to engage said carriage, and a timing device for releasing said catch from said carriage. 100

8. A target apparatus comprising an inclined track which rises from its rear toward its front end, a carriage mounted on said track and having a target and adapted to move backwardly by gravity, means for pushing said carriage forwardly, and means for temporarily holding said carriage in its foremost position comprising a catch arranged to engage said carriage and a timing device for releasing said catch from said carriage comprising a rail connected with said catch and adapted to incline alternately in opposite directions. 110

9. A target apparatus comprising an inclined track, which rises from its rear toward its front end, a carriage mounted on said track and having a target and adapted to move backwardly by gravity, means for pushing said carriage forwardly, and means for temporarily holding said carriage in its foremost position comprising a catch arranged to engage said carriage, and a timing device for releasing said catch from said carriage comprising a rail connected with 120

said catch and adapted to incline alternately in opposite directions, and means for pushing said carriage forwardly and tilting said rail.

5. 10. A target apparatus comprising a track which rises from its rear end toward its front end, a carriage mounted on said track and having a target, and adapted to move backwardly by gravity, a shifting lever adapted to push said carriage forwardly, a catch adapted to engage and hold said carriage temporarily in its foremost position, a vertically swinging rock lever connected with said catch and operatively connected 10 with said shifting lever, a tilting rail mounted on said rock lever, and a weight running on said tilting rail.
15. 11. A target apparatus comprising a track

which rises from its rear end toward its front end, a carriage mounted on said track and having a target and adapted to move backwardly by gravity, a shifting lever adapted to push said carriage forwardly, a catch adapted to engage and hold said carriage temporarily in its foremost position, a spring for holding said catch in engagement with said carriage, a vertically swinging rock lever connected with said catch, a line connecting the opposite end of said rock lever with said shifting lever, a tilting rail connected at its opposite ends with said rock lever and a weight having a trolley running on said rail alternately from one end to the other.

EWALD MEININGHAUS.
